UNITED STATES PATENT OFFICE.

CHARLES EDWIN HAMILTON, OF VAN NUIS, CALIFORNIA.

IRONING PAD.

Application filed May 1, 1923. Serial No. 635,853.

The invention relates to ironing pads as employed in ironing tables for pressing or in ironing machines, for example, of the character set forth in U. S. Letters Patent 5 No. 1,054,407, granted me the 25th day of February, 1913. The pad disclosed in said patent consists substantially of a base plate upon which are secured a plurality of adjacent and helically coiled springs, the latter 10 being covered by suitable caps which support a fabric top composed of a number of layers of suitable padding material.

The present invention has for its object to provide a substitute for the present type 15 of fabric padding generally employed in connection with ironing pads and especially in connection with the type of spring pad set forth in the aforesaid patent. In the type of resilient pad disclosed therein, it will be 20 noted that the fabric covering is in direct contact with metal, viz: the caps for the individual spring members; and the present invention, in addition to dispensing with a large proportion of the fabric padding 25 employed for the ironing surface, has for a further object to prevent contact of the latter with any metal portion of the pad as a whole. A still further object of the invention consists in providing an intermediate 30 and independently resilient medium between the actual ironing surface and the resilient support. In the provision of the intermediate resilient medium and especially in view of the elimination of overheating 35 thru prevention of direct metallic contact with the covering the wear on the latter is materially reduced and charring and burning of same obviated.

The nature of the invention, however, 40 will best be understood when described in connection with the accompanying drawings, in which—

Fig. 1 is a plan of one type of pad embodying the invention and with a portion 45 of the ironing surface cloth removed.

Fig. 2 is a fragmentary detail view illustrating the novel padding.

Figs. 3 and 4 are fragmentary views illustrating modifications. 50 Similar characters of reference designate corresponding parts thruout the several views.

Referring to the drawings, the pad may be 55 of various shapes, for example, of the flat type such as employed on an ironing table; but it will be understood that the padding

is suitable for the various shapes employed in ironing apparatus. The pad is shown as composed of a base plate 10 upon which is mounted a plurality of adjacently disposed resilient members, as the coil springs 11 with convolutions reduced at an end or ends and as is more particularly set forth in my U. S. Patent No. 1,466,363. These resilient members may be secured in any suitable manner 60 to the base plate, for example, as shown in the aforesaid U. S. Letters Patent; and at their tops may be covered with removable caps 12 similarly to the arrangement illustrated in the aforesaid Letters Patent. 70 They may further be secured against displacement from their springs, in manner more particularly shown in my U. S. Letters Patent No. 1,445,399, by providing an indentation 13 in the wall thereof, which indentation will then cooperate with the convolutions of the springs. 75

In accordance with the invention, the usual padding or covering is not supported by the tops of these caps 12 or by the tops 80 of the springs 11 as has been the practice heretofore and as is shown in my said Letters Patent; but there is carried by the individual springs, as in attaching to each individual cap or forming integrally therewith, 85 a suitable retainer member or receptacle 15. This member is of rigid material as metal and preferably in the nature of a cup which may be of various shapes, preferably hexagonal, as shown in Figs. 1 and 2, although 90 the square type illustrated in Fig. 3 provides for a satisfactory substantially closed surface. Where a slight opening between the tops is not objectionable, the round type of receptacle illustrated in Fig. 4 may be employed. Into these individual adjoining receptacles are fitted snugly or may be positively held thereby pieces or blocks of thermally insulating and heat resisting material 95 16, such as cork, asbestos or composition having proper resiliency for the purpose in view. These blocks are maintained against dislodgement by the rigid metal cups 15 and are arranged to project slightly above the edge thereof. Over the surface thus provided is usually to be stretched a single 100 layer or layers of finishing cloth 17, such as of duck or like material, which provides the ironing surface. For certain classes of work, however, such cloth covering may be 110 entirely omitted. By this expedient, not only is the pad

as a whole resilient thru the interposition of the springs 11, but each individual portion of the surface provided by blocks 16 affords an individually resilient surface portion; and the same need have but a single layer or two as of duck or similar material as a finishing surface for the ironing operation. Each individual surface portion, moreover, is securely retained in its receptacle and cannot become dislodged therefrom; and in projecting slightly about the edge of the receptacle separates and insulates the fabric surface material from any possible contact with any metal portion of the padding and thereby reduces the tendency to overheat. When it does become necessary to renew the fabric ironing surface, it is then not a case of providing an expensive pad composed of a considerable number of layers of material such as hair, cotton and wool of considerable thickness, but merely of recovering with one or two

layers of inexpensive material as duck, the more permanent cork or like material taking the place of same.

25

I claim:

1. An ironing pad, comprising a support composed of a plurality of adjacent resilient members, rigid retainer members carried thereby, and resilient and heat insulating members held therein to afford an ironing surface.

2. An ironing pad, comprising a support composed of a plurality of adjacent resilient members, receptacles individually carried by the said members, and individual heat insulating members fitting in and projecting above the edge of the receptacles to afford an ironing surface.

Signed at New York in the county of New York and State of New York this 28th day of April, A. D. 1923.

CHARLES EDWIN HAMILTON.
